(57) **CLAIM**

I claim the ornamental design for a football snapper machine, as shown and described.

DESCRIPTION

FIG. 1 is a perspective view of a football snapper machine, showing my new design;

FIG. 2 is a right-side elevational view thereof, the left-side elevational view being a mirror image thereof;

FIG. 3 is a top plan view thereof;

FIG. 4 is a bottom plan view thereof;

FIG. 5 is a front elevational view thereof; and,

FIG. 6 is a rear elevational view thereof.
